Primary Examiner — Nathaniel D. Buckner(74) *Attorney, Agent, or Firm* — ScienBiziP, P.C.(57) **CLAIM**

The ornamental design for a jump starter, as shown and described.

DESCRIPTION

FIG. 1 is a front perspective view of a first embodiment of jump starter showing the claimed new design;

FIG. 2 is a front elevational view of the jump starter of FIG. 1;

FIG. 3 is a rear elevational view of the jump starter of FIG. 1;

FIG. 4 is a left side elevational view of the jump starter of FIG. 1;

FIG. 5 is a right side elevational view of the jump starter of FIG. 1;

FIG. 6 is a top plan view of the jump starter of FIG. 1; and, FIG. 7 is a bottom plan view of the jump starter of FIG. 1. The broken lines in the drawings depict portions of the jump starter that form no part of the claimed design.
